(57) **CLAIM**

The ornamental design for an ice scraper with snow broom, as shown and described.

DESCRIPTION

FIG. 1 is a bottom perspective view of a first embodiment of the ice scraper with snow broom of the present invention; FIG. 2 is a top perspective view of the head of the ice scraper with snow broom of the first embodiment;

FIG. 3 is a rear top perspective view of the snow broom head of the ice scraper with snow broom of the first embodiment; FIG. 4 is a front top perspective view of the snow broom head of the ice scraper with snow broom of the first embodiment;

FIG. 5 is a rear elevational view of the snow broom head of the ice scraper with snow broom of the first embodiment; FIG. 6 is a top view of the snow broom head of the ice scraper with snow broom of the first embodiment;

FIG. 7 is a bottom view of the snow broom head of the ice scraper with snow broom of the first embodiment; FIG. 8 is a right end view of the snow broom head of the ice scraper with snow broom of the first embodiment;

FIG. 9 is a left end view of the snow broom head of the ice scraper with snow broom of the first embodiment; FIG. 10 is a front elevational view of the snow broom head of the ice scraper with snow broom of the first embodiment;

FIG. 11 is a rear top perspective view of a second embodiment of the ice scraper with snow broom of the present invention;

FIG. 12 is a front top perspective view of the head of the ice scraper with snow broom of the second embodiment;

FIG. 13 is a rear top perspective view of the snow broom head of the ice scraper with snow broom of the second embodiment;

FIG. 14 is a front top perspective view of the snow broom head of the ice scraper with snow broom of the second embodiment;

(Continued)

FIG. 15 is a rear elevational view of the snow broom head of the ice scraper with snow broom of the second embodiment;

FIG. 16 is a top view of the snow broom head of the ice scraper with snow broom of the second embodiment;

FIG. 17 is a bottom view of the snow broom head of the ice scraper with snow broom of the second embodiment;

FIG. 18 is a right end view of the snow broom head of the ice scraper with snow broom of the second embodiment;

FIG. 19 is a left end view of the snow broom head of the ice scraper with snow broom of the second embodiment; and,

FIG. 20 is a front elevational view of the snow broom head of the ice scraper with snow broom of the second embodiment.

The broken lines shown in the figures depict portions of the ice scraper with snow broom that form no part of the claimed design.
